(57) **CLAIM**

The ornamental design for a fiber optic cable, as shown and described.

DESCRIPTION

FIG. 1 is a top, front perspective view of a fiber optic cable, showing our new design;

FIG. 2 is a bottom, front perspective view thereof;

FIG. 3 is a front view thereof;

FIG. 4 is a left side view thereof;

FIG. 5 is a right side view thereof;

FIG. 6 is a top plan view thereof; and,

FIG. 7 is a bottom plan view thereof.

In the drawings, the evenly-spaced broken lines represent unclaimed subject matter and form no part of the claimed design. Additionally, the dash-dot-dash broken lines define the boundaries of the claimed design.
